UNITED STATES PATENT OFFICE.

SEVERN D. SPRONG AND WALTER E. MCCOY, OF NEW YORK, N. Y.

APPARATUS FOR RENDERING A PROTECTIVE DEVICE RESPONSIVE TO PHASE RELATIONS.

1,211,000.

Specification of Letters Patent.

Patented Jan. 2, 1917.

Application filed March 2, 1916. Serial No. 81,628.

To all whom it may concern:

Be it known that we, SEVERN D. SPRONG and WALTER E. MCCOY, citizens of the United States, residing at New York, in the county of New York and State of New York, have invented a certain new and useful Improvement in Apparatus for Rendering a Protective Device Responsive to Phase Relations, of which the following is a specification.

The invention is an apparatus embodying our method of rendering a protective device responsive to changes in phase relations, which method consists in establishing phase relations substantially 180° apart, and thus producing substantially no flux under normal conditions between two circuits normally out of phase, and each including means for generating mutually counteracting forces, whereby the said translating device is controlled by the unbalancing of said forces due to disturbances in the said established phase relations. We may apply this method in many devices, and for a great variety of utilizations. In our present apparatus, the object is the protection of a poly-phase motor against damage due to open wires or phase reversals, and the said apparatus is constructed so that a disturbance of phase relations between or the opening of either of the two circuits effects the blowing of a fuse in a relay circuit including the no-voltage release coil of a switch or circuit-breaker, thereby deenergizing said coil and permitting the switch to open circuit to the motor.

In the accompanying drawings Figure 1 is an electrical diagram, showing our apparatus. Figs. 2 to 9 are electrical diagrams illustrating certain principles underlying the same. Fig. 10 is an electrical diagram, showing the apparatus of Fig. 1 applied to a poly-phase motor to be protected. Fig. 11 is a detailed diagrammatic view of the fuse and contact finger.

Similar letters and numbers of reference indicate like parts.

The apparatus shown in Figs. 1, 10 and 11 consists in a shunt transformer, whereof 50 1 and 2 are primary coils connected to opposite phases of the two-phase three-wire supply circuits 3, 1, 4 and 5, 2, 4, through a non-inductive resistance 6 and a reactance 7. The relative values of the said resistance 55 and reactance are to be such that when the

coils 1, 2 are connected in said circuits, wherein the phase relations are normal, the currents in said coils 1, 2 shall be equal in value, and in opposition. In such case, no voltage is induced in the secondary coil 8 of said transformer. The terminals of said secondary coil are connected to the terminals of a fuse 9, Fig. 11, upon the body of which fuse bears a movable contact finger 10, to which one terminal of a relay circuit 11 is connected. The other terminal of said relay circuit is connected to one of the fuse terminals. In said relay circuit may be included a coil 12, which may be the no voltage release coil of a switch or circuit-breaker 13 to be opened, thus arresting the operation of a translating device, such as a poly-phase motor 14, Fig. 10, controlled by said switch 13. When through failure of current in either circuit 3, 1, 4 or 5, 2, 4 of the three-wire system, or through the displacement of the phases in said circuits, either coil 1 or 2 becomes deenergized, then sufficient current will be induced by the remaining energized coil in the secondary coil 8 to blow the fuse 9, thus interrupting the relay circuit, deenergizing the release coil 12, and permitting the switch 13 to be retracted by its springs, indicated at 15.

In Figs. 2 and 3 we have illustrated 85 graphically the current conditions in our apparatus for two and three-phase circuits. In Fig. 2, which relates to two-phase circuits, the line A, B represents the current in phase with the impressed voltage across the primary coil 1 in series with the non-inductive resistance 6. A, C represents the voltage across the primary coil 2 in series with the reactance 7. By reason of the reactance, the current in coil 2 lags 90 degrees 90 behind its impressed voltage and takes the position A, D, approximately 180 degrees from A, B. In Fig. 3, which applies to three-phase circuits, the line A, B represents the current in phase with the impressed 95 voltage across the coil 1, and A, C represents the current in phase with the impressed voltage across the coil 2. The current in the coil 2 lags 60 degrees behind its impressed voltage and takes the position A, D, approximately 180 degrees from A, B. Under these two normal operating conditions there will be a small resultant current A, E in the secondary 8 of the transformer, but this will be of sufficiently low value as 100 110

not to blow the fuse 9. Either coil 1 or 2 may become operative to induce current in the secondary by reason (a) of an interruption in the circuit 3, 1, 4 or 5, 2, 4 including that coil, or (b) when a change occurs in the phase relations of the circuits 3, 1, 4 or 5, 2, 4 respectively including said coils.

(a) It is obvious that if the current in either coil 1 or coil 2 be interrupted, the 10 remaining coil will continue to be energized, and hence, as already stated, will induce sufficient current in the secondary coil 8 to blow the fuse 9. The apparatus is thus operative on single phase circuit.

(b) In Figs. 4, 5, and 6, we illustrate conditions when by reason of a change in the normal phase relations, indicated in Figs. 2 and 3, a current is induced in the secondary 20 8 sufficient to blow the fuse 9 and open the relay circuit 11.

In the case of a two-phase three-wire circuit, only one of six possible conditions will produce the normal condition, Fig. 2. Under any other than the normal condition, 25 the resultant current A, E, Figs. 4 and 6, is sufficient to melt the fuse. In Fig. 4 the two potential leads 3, 5 are assumed to be crossed. The reactance is in the leading phase and the resistance is in the lagging phase.

In Fig. 6 a potential lead, as 3 or 5, and the neutral lead 4 are crossed, the reactance now being in the lagging phase and the resistance being across the potential leads. 35 Two-phase four-wire interconnected circuits provide twenty-four possible combinations, eight of which will produce rotation. Of these eight, four are normal and four are abnormal. Fig. 2 illustrates the normal 40 phase relation in this type of circuit, and Fig. 4 shows any of the abnormal conditions which will produce rotation and under which the resultant current A, E will blow the fuse.

Fig. 7 illustrates a two-phase four-wire interconnected circuit, and Figs. 8 and 9 indicate the phase relations under the conditions which will not produce rotation, but which will provide sufficient current to melt 50 the fuse.

In Fig. 7, F, H and G, I represent opposite phases of the supply circuit. When the windings of the transformer are connected to wires other than F, H and G, I, it is obvious that the phase relations will not be as indicated in Fig. 2, and that the voltage impressed on the windings will be but seven-tenths of the normal value. (The 55 square root of the sums of the squares of half the phase voltage). Under such conditions a motor will not operate, since, as shown in Fig. 9, the voltages A, C and A, B, connected to the motor windings, are 180 degrees apart. The effect of these voltages 60 on the transformer are shown in Fig. 8,

where due to the reactance in series with the transformer winding A, C, a resultant current A, E is produced of sufficient magnitude to melt the fuse.

It having thus been shown that the fuse 70 9 will be melted in the event of any phase reversal, or in case either supply circuit becomes open, the resultant operation of the switch or circuit-breaker insures a positive protection to the translating device against 75 possible damage resulting from these conditions.

We claim:

1. An apparatus for rendering a protective device responsive to changes in phase 80 relations, comprising a primary formed of two counter-balancing coils, a secondary, and a circuit-controlling device in circuit with said secondary; whereby upon the disturbance of the balance between said primary 85 coils, the said controlling device shall be operated by the current induced on said secondary.

2. An apparatus for rendering a protective device responsive to changes in phase 90 relations, comprising a primary formed of two counter-balancing coils, a secondary, a circuit including said secondary, and means for opening said circuit operated by the current induced on said secondary when said 95 current shall have attained a predetermined value.

3. An apparatus for rendering a protective device responsive to changes in phase 100 relations, comprising a primary formed of two counter-balancing coils, a secondary, a circuit including said secondary, a no-voltage release magnet in said circuit, and a switch lever controlled by said magnet, and a translating device in relay circuit with 105 said switch lever.

4. An apparatus for rendering a protective device responsive to changes in phase relations, comprising a primary formed of two counter-balancing coils, a secondary, a 110 circuit including said secondary, a fuse in said circuit, and a translating device in relay circuit with said fuse.

5. An apparatus for rendering a protective device responsive to changes in phase 115 relations, comprising a primary formed of two counter-balancing coils, a secondary, a circuit including said secondary, a no-voltage release magnet in said circuit, a switch lever controlled by said magnet, and a translating device in relay circuit with said 120 switch lever.

6. An apparatus for rendering a protective device responsive to changes in phase 125 relations, comprising a primary formed of two counter-balancing coils, a secondary, a circuit including said secondary, an exposed fuse strip having its terminals connected in said circuit, a spring arm bearing on said fuse strip between said terminals, a relay 130

circuit connected to one of said fuse terminals and to said spring arm, and a translating device in said relay circuit.

7. A protective apparatus for a poly-phase motor, comprising a supply circuit therefor, two circuits in shunt with said supply circuit and receiving different phase current therefrom, two primary coils respectively disposed in said phase circuits and connected in opposition, a secondary, a fuse in circuit with said secondary, and a relay circuit including said fuse, said release magnet and said motor.

10 8. A protective apparatus for a poly-phase motor, comprising a supply circuit therefor, a switch in said circuit, a no-volt-

age release magnet controlling said switch, two circuits in shunt with said supply circuit and receiving different phase currents therefrom, two primary coils respectively 20 disposed in said phase circuits and connected in opposition, a secondary, a fuse in circuit with said secondary, and a relay circuit including said fuse, said release magnet and said motor.

25 In testimony whereof we have affixed our signatures in presence of two witnesses.
